DISPLAY UNIT

John Stuart MacDonald, Rochester, N. Y.

Application April 8, 1938, Serial No. 200,965

3 Claims. (Cl. 211—72)

This invention deals with a display unit or display stand useful in stores and the like, for displaying an article of merchandise or advertising or reading matter relating to merchandise, in an attractive manner.

An object of the invention is the provision of a simple and effective display unit or stand which can be easily and quickly erected from a substantially flat form to an erected or three-dimensional form.

Another object is the provision of such a display unit so designed and constructed that it will be automatically locked in erected position by the mere act of moving the main parts to erected position, the locking means holding the unit against accidental collapse.

A further object is the provision of a display unit which, when in erected position, will provide a stable base on which other articles may be placed, said base preferably including an elevated platform or step.

To these and other ends the invention resides in certain improvements and combinations of parts, all as will hereinafter be more fully described, the novel features being pointed out in the claims at the end of the specification.

In the drawings:

Fig. 1 is a front elevation of a display unit constructed according to a preferred embodiment of the present invention, in erected position;

Fig. 2 is a rear elevation of the same;

Fig. 3 is an end elevation of the same;

Fig. 4 is a perspective view of the same;

Fig. 5 is a section taken substantially on the line 5—5 of Fig. 3, illustrating features of the lock which holds the unit in erected position;

Fig. 6 is a section taken substantially on the line 6—6 of Fig. 5;

Fig. 7 is a view of the display unit in flat or non-erected form;

Fig. 8 is a front elevation of a modified form of display unit, in erected position;

Fig. 9 is an end elevation thereof;

Fig. 10 is an inverted perspective view of a fragment of the erected unit, showing the construction of the locking device.

Fig. 11 is a view thereof in flat or non-erected position;

Fig. 12 is a front elevation of still another modified form of construction, in erected position;

Fig. 13 is an end view thereof;

Fig. 14 is a plan of the construction shown in Figs. 12 and 13, in flat or collapsed form, and

Fig. 15 is a sectional view through one of the

hinge joints of the sheet material from which the display unit is made.

The same reference numerals throughout the several views indicate the same parts.

Referring first to the preferred embodiment illustrated in Figs. 1 to 7, there is provided a unit preferably formed from only two separate pieces of suitable sheet material, such as fiber board, cardboard, box board, etc. The first or larger of these pieces comprises two sections 21 and 22 10 hinged to each other about the score line 23. Two other or secondary sections 24 and 25 are formed from the same piece, by cutting the ends of the sections 24 and 25 free from the sections 21 and 22, inwardly from the marginal edges 15 thereof, as plainly seen in Fig. 7, the section 24 remaining fastened to the section 21 along the score line 26 which forms a hinge joint, the section 25 remaining fastened to the section 22 along the score line 27 which forms another hinge joint, 20 and the sections 24 and 25 remaining fastened to each other on the hinge joint score line 28.

The various score lines referred to above and hereafter may be either pressed scores, cut scores, or of any other suitable known form. If the sheet material be relatively thin, pressed scores may be used, and if the sheet material be relatively thick, cut scores (cut partially but not entirely through the thickness of the sheet material) are preferably employed.

The second piece of sheet material forming the unit is a strip secured to the underside of one of the secondary sections of the first piece of sheet material. In the illustrative embodiment here shown the second piece is secured to the under side of the section 24, and comprises a central section 30 underlying the section 24 and secured thereto in any suitable manner, such as staples, rivets, adhesive, etc., adhesive being preferred. The strip of sheet material is longer than the length of the section 24, and projects beyond the section 24 at both ends, the projecting ends forming flaps 31 hinged to the central portion 30 by the score lines 32 (Fig. 5). The section 30 may be made in two pieces if desired, the middle portion being omitted.

When the unit is in flat or collapsed form, the first mentioned piece of sheet material, from which the sections 21, 22, 24 and 25 are made, lies substantially flat in one plane, and the sections 30 and 31 of the second piece of sheet material also lie flat in one plane against the back surface of the main or first sheet. When the device is to be erected, the sections 21 and 22 are grasped and bent around the hinge line 23 so as to lie at a sub-

stantial angle to each other, a right angle being preferred (but other angles being possible by varying the construction), and the action of bending up the sections 21 and 22 will at the same time 5 automatically bend the sections 24 and 25 at angles to each other and to the sections 21 and 22, to form a step-like projection or platform in the interior angle between the sections 21 and 22. It is seen that sections 21, 22, 24 and 25 form approximately a parallelogram when viewed endwise as in Fig. 3 so that the secondary sections 24 and 25 do not in any way interfere with bending the main sections 21 and 22 at different angles relatively to each other.

15 As the sections 21 and 22 are bent up, the section 24 is moved farther and farther away from the plane of the section 22, and this automatically bends down the sections or flaps 31 of the second 20 piece of sheet material for these flaps can no longer remain in the plane of their body section 30, and are forced downwardly by contact of the overlying parts of the section 22. Finally, when 25 erection is completed, the flaps 31 form walls substantially closing the ends of the step-like projection or platform formed by the sections 24 and 25.

According to one feature of the present invention, the end flaps 31 are utilized to lock the device in erected position and prevent accidental collapse thereof. This locking may be accomplished by causing the flaps 31 to abut against one or more surfaces of the sections 21 and 22, in locking or latching relation thereto. In the form 30 here shown, the latching engagement takes place between the rear edge 33 of each flap 31 and the front surface of the section 21, which section is for this purpose extended as at 34 so as to cross the plane of the flaps 31 when the flaps are in erected position.

It is seen that, assuming the unit is standing in 40 the erected position shown in Figs. 3 and 4, it cannot collapse from this erected position without causing movement of the section 24 either backwardly or forwardly with respect to the section 22, for any change in the angle between the sections 45 21 and 22 will have the effect of moving the section 24 with relation to the section 22. Since the flaps 31 are mounted on the section 24, they must move backwardly or forwardly with the section 24. But the portion 34 at the bottom of the section 21 lies in the path of movement of the bottom 50 end of the rear edge 33 of the flap 31, and prevents rearward movement of the flap 31, thereby preventing rearward movement of the section 24 with relation to the section 22, and preventing collapse 55 of the sections 21 and 22 to their original flat condition. Similarly, if it be attempted to collapse the unit by folding the section 21 forwardly down onto the top of the section 22 this is prevented by reason of the forward upright edge of 60 the flap 31 lying against the rear face of the section 25 just inside the end edge thereof, which prevents the forward movement of the flap 31 which would be required for such collapsing.

In this way, the flaps 31, when in effective locking position, prevent collapse of the display unit 65 in any direction. Yet it is but the work of an instant to collapse the unit when it is desired to do so, by pressing the flaps 31 inwardly until they clear the portions 34 of the section 21, whereupon they can slide rearwardly past such portions 34 and the device can be collapsed to its original flat form shown in Fig. 7.

According to the preferred form of the present invention, resilient means is provided, tending to move the flaps 31 to locking position. While sep-

arate resilient means, such as suitably arranged rubber bands, springs, or the like, may in some instances be employed, it is ordinarily preferred that the resilient means be provided by the resiliency of the sheet material which makes up the parts 30 and 31. If a cut score is used at the junction or hinge 32 between the parts 30 and 31, care is taken to allow sufficient thickness of material to remain so that such material has a springy or resilient effect. Hence, the resiliency of the material will tend to keep the flaps 31 in the same plane with the central portion 30 between these flaps. When the unit is bent up from its flat condition to its erected condition, the overlying relation of the section 22 to the flaps 31 automatically bends these flaps downwardly out of the plane of the portion 30 as the erecting operation proceeds, and this downward bending is resisted by the inherent resilience of the material at the hinge joint 32, which resilience constantly tends to move the 20 flaps 31 upwardly to their original position in the same plane with the section 30. Consequently, as soon as the erection proceeds sufficiently far so that the rear edges of the flaps 31 are brought just in front of the front surface of the portions 34, 25 the resilient action immediately snaps the flaps 31 outwardly as far as they are permitted to go (the lower end of each flap contacting with the edge 36 of the section 22, to limit such outward movement), and the locking action is thus effective. 30 The flaps 31 which form the ends of the step or platform 24, 25, etc., may be placed at any convenient or desired angle, whether vertical or oblique to the section 22. An oblique inclination, such as shown in Figs. 1, 2, 4, and 5, is usually 35 preferred.

When the device is erected, either of the walls or sections 21 and 22 may form the base of the device and the other of such walls will stand upright. The article to be displayed, or a facsimile 40 or dummy thereof, may be placed on the step or platform formed by the parts 24 and 25, or on any other suitable part of the device. If desired, one or more additional steps or platforms may be formed, in the angle between the parts 21 and 24, 45 or in the angle between the parts 22 and 25, or in both such angles, or one or more larger or smaller steps may be formed in the main angle between the parts 21 and 22 and in endwise relation to the step above described. The lock for 50 holding the parts in erected position may be formed wholly or in part between a large step and a smaller step in endwise relation to each other, utilizing the same locking principles herein disclosed. For purpose of illustration one additional step is here shown in the angle between the parts 21 and 24, this step being formed by the sections 41 and 42, the former of which is hinged to the section 21 by the score line 43, and the latter of which is hinged to the section 24 by the 55 score line 44. The two sections 41 and 42 are hinged to each other at the score line 45.

Referring now to the modified form of construction shown in Figs. 8 to 11, inclusive, this modified construction embodies the same principles, the main difference being that the locking flaps 31 of the embodiment previously disclosed are extended rearwardly as shown at 31a, to project a substantial distance on the opposite side of the plane of the section 21 when the device is erected, in order to provide a broader base and hold the display unit against accidentally tipping backwardly, when the section 22 is placed flat on a table, counter, or other support. On the other hand, if the section 22 is placed in up-

right position with the section 21 on the table or counter, the unit will be supported by the ends of the rearward extensions 31a and by the remote edge of the section 21, so that the section 5 21 will be supported at an angle to the top of the table or counter on which it is placed.

In order to adapt the parts to this extension 31a of the locking flaps 31 the locking shoulders 34 of the previous embodiment of the invention 10 are reduced in size as shown at 34a in Figs. 10 and 11, and a notch 31b is provided in the locking flap 31, to cooperate with the locking shoulder 34a when the parts are erected. When in erected 15 position, the front edge of the notch 31b lies against the front surface of the locking lug or shoulder 34a, as shown especially in Figs. 9 and 10, to prevent rearward movement of the flap 31 with respect to the sections 21 and 22, and thus 20 to prevent collapse of the device. Forward collapse is prevented as before, by contact of the front edge of the flap 31 with the rear surface of the section 25. The provision of a relatively 25 small locking lug or shoulder 34a to enter the notch 31b permits the rest of the edge 37 of the section 21 to extend in a straight line from the junction of the edge 33 with the score line 23, up to the score line 26, so that the rest of the flap 31 (above the top of the notch 31b) may extend straight upwardly along this edge 37.

30 Except for the changes above mentioned, the embodiment illustrated in Figs. 8 to 11 may be the same as that illustrated in Figs. 1 to 7, and the same reference numerals have been used in both embodiments for the corresponding parts.

35 Referring now to the modified embodiment illustrated in Figs. 12 to 14, this also includes main sections 21 and 22, and secondary sections 24 and 25, together with the same score lines as in the previous embodiments. The main difference here 40 is that the locking flaps 31c, instead of bearing at their rear edges against the front face of the section 21 or a special locking shoulder or lug thereon, here bear against and interlock with notches 36c formed in the edge 36 of the section 45 22. The locking flaps 31c have projections or lugs 31d to engage in these notches 36c when the display unit is in erected position. As before, the resiliency of the hinge joint between the locking flaps 31c and the parts on which they are mounted tends to swing these flaps 31c outwardly so 50 that as soon as the lugs 31d are brought into alignment with the notches 36c during the erecting operation they will snap automatically into these notches to lock the parts in erected position.

55 Except for the differences above mentioned, the parts of this embodiment may be the same as those of the embodiments previously described, and the same reference numerals have been used 60 for corresponding parts.

Fig. 15 illustrates a detail of any one of the score lines or hinge joints, such as the hinge joint line 23 between the sections 21 and 22. It is simply intended to illustrate a cut score through

part of the thickness of a relatively thick or heavy piece of sheet material.

The sections 21 and 22 may be made rectangular, semi-circular, or of any other plain or fancy shape, without departing in any way from the 5 present invention, and each of the steps or platforms (whether one or more be used) may be of any desired shape or size.

While certain embodiments of the invention have been disclosed, it is to be understood that 10 the inventive idea may be carried out in a number of ways. This application is therefore not to be limited to the precise details described, but is intended to cover all variations and modifications thereof falling within the spirit of the 15 invention or the scope of the appended claims.

I claim:

1. A collapsible and erectable unit including sheet material cut and scored to provide four wall sections hingedly connected to each other 20 so that they may be moved from an approximately flat collapsed position to an erected position forming a body of approximately rectangular outline when viewed from one end, a locking flap mounted on and hingedly connected to one of 25 said wall sections adjacent one edge thereof so that said flap may form an end of said body when it is in erected position, a portion of said flap engaging with a portion of another of said wall sections to lock said sections against collapse, 30 and resilient means tending to move said flap into cooperative locking engagement with said other wall section so that said flap will automatically snap into locking position when said wall sections are moved from collapsed position 35 to erected position.

2. A unit as described in claim 1, in which said resilient means is the inherent resiliency of the material forming the hinge joint of said locking flap.

3. A collapsible and erectable unit including a single piece of sheet material cut and scored to provide two main sections hinged to each other and arranged to be moved from relatively flat position to erected position at a substantial angle 40 to each other and two secondary sections cut from the main sections inwardly of the marginal edges thereof and hinged to the main sections and to each other and arranged to be moved from relatively flat position lying approximately in 45 the plane of said main sections to erected position forming a step-like projection in the interior angle between said main sections when said main sections are moved to erected position, and a second piece of sheet material secured to the under 50 side of one of said secondary sections and projecting materially beyond such section at both ends when said unit is in flat condition, the projecting ends of said second piece of sheet material bending down when said unit is erected to 55 form closed ends for said step-like projection and having latching engagement with one of said main sections to hold all of said sections in erected position.

JOHN STUART MACDONALD.
